DISCONNECTER

Wesley Wilson, Chicago, Ill.

Application June 6, 1934, Serial No. 729,206

5 Claims. (Cl. 294—20)

My invention relates to fixture disconnecters. One of the objects of my invention is to provide a fixture disconnector having a pole and fixture gripping means in which, in addition to manual control for the gripping means at the lower end of the rod, another manual controlling means is provided adjacent the gripping means.

A further object is to provide improved means for supporting the end of the pole adjacent the gripping means in such a manner that that end of the pole and fixture supported thereby can be held at a distance from the floor for convenience in manipulation.

A further object is to provide a fixture disconnector in which the gripping means will hold the fixture with a resilient action in order to prevent injury to the fixture.

Further objects and advantages of the invention will appear from the description and claims.

In the drawing, in which my invention is shown,

Figure 1 is an axial section of a fixture disconnector embodying my invention;

Fig. 2 is a detail view of the upper gripper operating device;

Fig. 3 is a section on the line 3—3 of Fig. 2;

Fig. 4 is a section on the line 4—4 of Fig. 1; and

Fig. 5 is a perspective view showing the legs unfolded in supporting position.

Referring to the drawing in detail, the construction shown therein comprises a tubular pole 1, a jaw carrying sleeve 2 splined on the upper end of the tubular pole, a plurality of gripping jaws 3 pivotally mounted on this sleeve at 4 for gripping the rim of a reflector 5, an operating handle 6 for effecting gripping engagement of the jaws on the shade swingable on the lower end of the pole, another gripper operating member 7 for controlling the jaws swiveled on the upper end of the tubular pole, and a pair of supporting legs 8 pivotally mounted on a collar 9 secured adjacent the upper end of the pole.

The transmission from the lower operating handle 6 to the jaws 3 comprises a rod 10 slidably but not rotatably mounted in the tubular pole and having an adjustable follower pin 11 cooperating with a face cam 12 in the hub portion 13 of the lower swiveled handle member 6, a plunger 14 slidably mounted in the upper end of the tubular pole, and a stiff coil spring 15 connecting the plunger and rod.

To tighten the jaws to cause them to grip the shade, the handle 6 is turned to cause the face

cam 12 to force the follower pin 11 downwardly, thus drawing the plunger pin 14 downwardly and pressing the head 16 at the upper end of the plunger downwardly against the inner ends of the pivoted gripping jaws 3 to cause these jaws to snugly engage the rim of the shade 5. The stiff tension spring 15 between the operating rod 10 and the plunger 14 prevents unyielding action of the jaws which might tend to injure the rim of the shade. To release the jaws, the operating handle 6 is turned in a direction to allow the follower pin 11 to move upwardly, thus allowing the jaw opening spring 17 to force the plunger upwardly to disengage the jaws from the shade.

In the above-described operation of the lower operating handle, the upper operating handle is placed in a position in which the jaw-carrying sleeve 2 is in its uppermost position, as shown in Fig. 2. This upper gripper controlling handle 7 is useful when the pole is in lowered position, as shown in Fig. 5, as it enables the operator to control the jaws for gripping or releasing from a position in which he is enabled to manipulate the shade also. To release the jaws by means of the upper operating handle 7, this handle is turned to a position in which the cam members 18 on the hub 19 of the handle are in position to allow the splined jaw-carrying sleeve 2 to be moved to its lower position under the action of the coil compression spring 17, thus causing the gripping jaws 3 to expand to release the shade. The lower cam face of the splined jaw-carrying sleeve 2 is provided with suitable positioning notches 20 for cooperation with the upper ends of the cam projections 18 on the hub of the operating handle, as shown in Fig. 2, the coil compression spring 17 serving to hold the parts in the position shown in Fig. 2 when the jaws are to be operated by the lower operating handle 6. The splined connection between this jaw-carrying sleeve 2 and the tubular pole 1 is effected by means of a pin 21 secured to the sleeve, having its inner end slidable in a slot 22 in the tubular pole. The non-rotatable connection between the rod 10 and the tubular pole 1 is effected by means of a pin 23 on the rod slidably engaging a slot 24 on the lower end of the tubular pole. In order to vary the spread of the jaws for different sizes of shades, the pin follower 11 in the lower end of the sliding rod 10 can be inserted in any one of a number of holes 25 in the lower end of the rod. For a small shade, the pin is

placed in the upper hole and for a large shade the pin is placed in the lower hole.

The supporting legs 8 are pivotally mounted at 26 on lugs 27 formed on the collar 9 which is secured to the tubular pole 1 underneath the hub 19 of the upper operating handle 7. The legs and lugs may be provided with cooperating positioning means 28, 29 for holding the legs either in position folded against the tubular pole 1 or 10 in extended position as shown in Fig. 5.

In use, in connecting the fixture, the pole 1 is placed in the position shown in Fig. 5, the shade 5 is secured to the gripping jaws 3 by means of the upper operating handle 7, the legs 15 8 are folded against the side of the pole, and the pole is then used as a handle to elevate the shade and effect the necessary movements to connect the fixture with the ceiling unit. When this connection has been effected, the gripping jaws 3 are released by operating the lower operating handle 6, whereupon the pole can be lowered, leaving the shade and fixture in connected position. To disconnect the fixture, the operation is reversed. The lower handle 6 is operated 20 to move the gripping jaws 3 to extended position, the pole is then elevated to bring the jaws 3 in position to grip the edge of the shade, the lower handle 6 is operated to cause the jaws 3 to engage the shade yieldingly and the pole is 25 then given the necessary motion to effect the disconnection between the fixture and the ceiling unit. The pole carrying the fixture is then lowered to the position shown in Fig. 5 and the legs 30 extended to support the fixture. The upper operating handle 7 is then operated to release the jaws, whereupon the fixture can be inspected, cleaned, etc.

Further modifications will be apparent to those 40 skilled in the art, and it is desired, therefore, that my invention be limited only to the prior art and the scope of the appended claims.

Having thus described my invention, what I claim and desire to secure by Letters Patent is: 45

1. A fixture disconnector comprising a pole, fixture gripping means mounted on the upper end of the pole, means for closing the gripping means on the fixture and retaining the gripping means in gripping position comprising manually operable means carried by the pole adjacent the lower end thereof, means for transmitting manually exerted force from said manually operable means simultaneously with the exertion of said force for closing the gripping means and for retaining the gripping means in closed position when said manual exertion is discontinued, and means for releasing the gripping means from the fixture against the action of said retaining means

comprising manually operable means carried by the pole adjacent the fixture gripping means.

2. A fixture disconnector comprising a pole, fixture gripping means mounted on the upper end of the pole, means for closing the gripping means 5 on the fixture and retaining the gripping means in gripping position comprising manually operable means carried by the pole adjacent the lower end thereof, means for transmitting manually exerted force from said manually operable 10 means simultaneously with the exertion of said force for closing the gripping means and for retaining the gripping means in closed position when said manual exertion is discontinued, and means for releasing the gripping means from the fixture against the action of said retaining means and for closing and retaining the gripping means in gripping position on the fixture comprising manually operable means carried by the pole adjacent the fixture gripping means. 15

3. A fixture disconnector comprising a pole, fixture gripping means mounted on the upper end of the pole, manually operable gripper controlling means mounted adjacent the lower end of the pole, and supporting means carried by the 20 pole adjacent the upper end thereof for supporting the fixture at a convenient height from the floor, said supporting means comprising a pair of legs each having a hinge connection with respect to the pole adjacent the upper end thereof, said legs being mounted for swinging movement from a position in which they are folded so as to lie adjacent the pole and parallel to each other and to the pole to a supporting position in which they extend at an angle to each other 25 and radially with respect to the pole.

4. A fixture disconnector comprising a pole, a fulcrum member mounted on said pole for longitudinal movement with respect thereto, a plurality of fixture gripping jaws fulcrumed on said 40 fulcrum member, means for effecting longitudinal movement of the fulcrum member with respect to the pole to effect movement of the jaws, and means for effecting opening and closing movement of the jaws when the fulcrum member 45 is stationary with respect to the pole.

5. A fixture disconnector comprising a pole, a fulcrum member mounted on said pole for longitudinal movement with respect thereto, a plurality of fixture gripping jaws fulcrumed on said 50 fulcrum member, means adjacent one end of said pole for effecting longitudinal movement of the fulcrum member with respect to the pole to cause movement of the jaws, and means adjacent the other end of the pole for effecting movement of 55 the jaws when the fulcrum member is stationary with respect to the pole.

WESLEY WILSON.
